UNITED STATES PATENT OFFICE.

JOSEF KUSH, OF FRANKLIN, PENNSYLVANIA.

DESIGN FOR A PICTURE-FRAME.

60,045.

Specification for Design.

Patented Dec. 20, 1921.

Application filed June 30, 1921. Serial No. 481,658. Term of patent 3½ years.

To all whom it may concern:

Be it known that I, JOSEF KUSH, a citizen of Poland, residing at Franklin, in the county of Venango and State of Pennsylvania, have invented a new, original, and ornamental Design for Picture-Frames, of which the following is a specification, reference being had to the accompanying drawing, forming a part thereof.

The figure is a perspective view of my picture frame, showing my design.

I claim:

The ornamental design for a picture frame, substantially as shown.

JOSEF KUSH.
